DOLL'S HOUSE STRUCTURAL SET

Gisela Guelicher, Brooklyn, N. Y.

Application June 29, 1946, Serial No. 680,453

2 Claims. (Cl. 46—19)

1

This invention relates to dolls' houses or the like, and aims to provide, in combination, a base having a plurality of vertical grooves extending thereinto from the top and extending longitudinally, transversely, or at an angle, along the base, and a plurality of construction elements such as walls or the like which are adapted to be mounted to form a house or the like merely by inserting the walls into the said grooves. The various grooves shown in the drawing are in straight lines, although curved grooves may be used in addition. Also, only walls are illustrated as registering in the grooves, but other parts or articles might also be so applied, such as, for instance, pieces of furniture, posts, as well as numerous other things which may enhance the enjoyment of the toy.

A further object of the invention is the provision of the base in a plurality of sections hinged together, so that the base may be reduced to a compact mass when not in use, for storage etc. As the base is hollow and thus provides space inside the sections thereof, the walls, etc., supplied with the toy may be stored in the hollow base sections when not in use, and for this purpose doors or the like, not shown, may be provided in one vertical wall of each base section.

The above as well as additional objects will be elucidated in the following description, wherein characters of reference refer to like-numbered parts on the drawing. It is to be noted that the drawing is intended solely for the purpose of illustration, and that it is neither desired nor intended to limit the invention necessarily to any or all of the exact details of construction excepting insofar as they may be deemed essential to the invention.

Referring briefly to the drawing,

Fig. 1 is a perspective view showing the base with one structure fully and another partly erected and mounted thereon.

Fig. 2 is a plan view of the base per se.

Fig. 3 is a sectional view taken on the line 3—3 of Fig. 2.

Fig. 4 is an enlarged, fragmentary side elevational view of the base, showing the countersunk hinges used thereon.

Fig. 5 is a fragmentary side elevational view of a mutually-hinged sectional roof member.

Fig. 6 is a fragmentary end elevational view of the same.

Fig. 7 is a vertical sectional view illustrating the manner of providing a two-storied structure, including a hollow floor and ceiling member.

2

Fig. 8 is a view similar to Fig. 7, but showing a modified form of construction.

Referring in detail to the drawing, the numeral 10 indicates a hollow base formed of three sections hinged together by means of countersunk hinges 12, the three sections being indicated at 13, 14, and 15.

One end section, 13, comprises the bottom plate 16, having the upright walls 17, 18 and 19. 10 The inner end wall 20 extends across the space left on that side, but terminates at a distance from the walls 18 and 19 thereby leaving a space 21 at each end of the wall 20.

Mounted within the enclosure of the 18, 19, 20, and 17, are a pair of platform-like members 22, each having the four upright walls 23, 24, 25, and 26; the walls 23 are spaced from the wall 17 by a distance equal to the space 21; in the same manner the wall 26 is spaced from the wall 13 and the wall 24 is spaced from the wall 20; likewise, the wall 25 of the one member 22 is separated from the wall 26 of the adjacent member 22 by the same distance. The walls 23—26 are supported in fixed position on the base 16 by any suitable means or in any desired manner, as, for instance, by glue or screws, not shown, and they are preferably although not necessarily made of wood. Thus, grooves 27, 28, 29, 30, and 31 are provided in the floor of the base member 10.

30 In the same manner platform members 22a are provided in the section 14, and members 22b and 22c, the latter of smaller dimensions, in the section 15. These grooves 27—31 as described are presented merely by way of example, as any other 35 geometric pattern of the platform-like members may be provided to give different arrangements of grooves, either straight or curved, in an obvious manner.

In Fig. 1 the base 10 is shown, provided with 40 additional grooves 32 and 33 as shown in Fig. 2 also. By way of example, walls 34, 36, and 35 are shown on the right, Fig. 1. It is to be noted that the grooves 30, 30a and 30b and the spaces 21 and 21a, at the top, Fig. 2, provide a continuous groove nearly the length of the base 10; in the same manner all the grooves and spaces 21 are in alignment to provide a continuous groove along the other side of the base 10. The wall 34 registers in the latter groove, and the wall 36 as 50 well as the door 35 both register in the transverse groove 33, as does also the wall 37. The wall 38 registers in the groove 31b, and the wall 39 registers in the groove 27b. Of course only one example has thus been offered of the many possible 55 arrangements of walls etc. in the various grooves.

Figs. 7 and 8 offer methods of construction whereby two-story houses may be erected. In Fig. 7, a double side wall 40 has the two spaced boards 41 and 42 separated by a spacer strip 43, the lower edges of the walls 41 and 42, not shown, being adapted to register in any pair of adjacent grooves such as, for instance, grooves 20 and 21a. The spacer 43 is adapted to run the full length of the wall, and is provided with a groove 44 throughout its length. The double floor 45 comprises the upper and lower boards 46 and 47, the former being the floor of the second story and the latter the ceiling of the first, separated by one arm 48 of a spacer strip 49. The other arm 50 of the strip 49 extends upward, and between the arms is a vertical groove 51. The two boards 52 and 53 form the upper wall 54, and they are erected by having their lower edges register in the grooves 51 and 44, respectively. In the modified form of Fig. 8, parts which are similar to Fig. 7 bear the same reference numeral followed by the letter "a." In this case the second story wall is a single board registering in the groove 44a, and a square spacer strip 56 separates the floor boards 46a and 47a.

To provide suitable peaked roofs for the walls, roof members are provided in two or more sections 57 joined by hinges 58. Along the longitudinal edges of each section 57, a moulding strip 59, having the longitudinal groove 60 in its underside, is provided, in which the upper edges of the walls at the ends, such as wall 36, register.

From the above description it is apparent that a doll's house toy or set has been provided, wherein the various component parts including walls, roofs, etc., as well as other elements such as furniture and the like, may all be furnished as separate pieces, parts or members, in combination with the base 10 which is provided with the desired assortment of grooves therein in the manner stated. Then the child may erect a large varied assortment of structures and furnish them as desired, with the exercise of the skill of the child and the elimination of boredom owing to the variability of the arrangement permitted.

And when not in use, the structures may be readily dismantled, as is apparent, and the base 10 collapsed into a compact mass for convenient storage. The dismantled elements of the structures, that is, the walls, roofs, etc., may, as stated, be placed within the compartments contained in the sections of the base. It is to be noted that no screws, clamps, or any other means of securing the walls to the base or the other parts men-

tioned to the walls, are required, as the registration of the walls, etc., in the grooves, as mentioned, is sufficient to provide fixed interengagement of the various parts.

Obviously, modifications in form and structure may be made without departing from the spirit or scope of the invention.

I claim:

1. A toy structural set comprising a base having a plurality of grooves extending downward through the upper surface thereof and arranged in patterns thereon, a plurality of walls having their lower edges registrable selectively in said grooves of any of said patterns to provide the enclosing walls of house-like structures, each of said walls comprising spaced parallel boards and spacer strips therebetween, combined floor and ceiling members supportable on said walls by having the ends of said members rest on said spacer strips, said floor and ceiling members comprising spaced boards having spacer strips therebetween, said spacer strips having spaced vertical grooves extending therealong, and second story walls comprising spaced parallel walls adapted to register in said last-named grooves.

2. A toy structural set comprising a base having a plurality of grooves extending downward through the upper surface thereof and arranged in patterns thereon, a plurality of walls having their lower edges registrable selectively in said grooves of any of said patterns to provide the enclosing walls of house-like structures, each of said walls having a strip along the top edge thereof, said strip having a longitudinal groove intermediate the edges thereof in its upper surface, a second story wall registrable in said strip groove, and a combined floor and ceiling member supportable at one end by said strip by resting on the upper surface of said strip adjacent said strip groove.
